DESIGN FOR A BRACELET OR SIMILAR ARTICLE

Emil E. Fachon, Edgewood, R. I., assignor to Bulova Watch Company, Inc., New York, N. Y., a corporation of New York

Application May 26, 1948, Serial No. 146,606

Term of patent 7 years

(Cl. D45—4)

To all whom it may concern:

Be it known that I, Emil E. Fachon, a citizen of the United States, residing at 12-A Sefton Drive, Edgewood, county of Providence, and State of Rhode Island, have invented a new, original, and ornamental Design for a Bracelet or Similar Article, of which the following is a specification, reference being had to the accompanying drawing, forming part thereof.

Fig. 1 is a top plan view of a bracelet, showing my new design;

Fig. 2 is a side elevational view of the bracelet;

Fig. 3 is a bottom plan view thereof;

Fig. 4 is a top plan view of a portion of the bracelet with links in an expanded position; and
Fig. 5 is an end elevational view taken from the right of Fig. 4.

The links shown in full lines are repeated across the length of the bracelet as indicated by the broken line disclosures in Figs. 1, 2 and 3.

I claim:

The ornamental design for a bracelet or similar article, as shown and described.

EMIL E. FACHON.
